PILOT VANE FOR THE AEROFOIL WINGS OF AIRPLANES

Filed June 15, 1929

Inventor:
H. J. Kratzer.
By Herbert G. Fletcher, Atty.

UNITED STATES PATENT OFFICE

HERBERT J. KRATZER, OF ST. LOUIS, MISSOURI

PILOT VANE FOR THE AEROFOIL WINGS OF AIRPLANES

Application filed June 15, 1929. Serial No. 371,113.

This invention relates to an improved pilot vane for the aerofoil wings of airplanes and has for its primary object the purpose of providing an improved pilot vane which is capable of cooperating in a manner with the wings of the plane whereby the load sustaining ability of the wing surface will be greatly increased.

Another object of the invention is in providing an improved pilot vane which will cooperate with the aerofoil wings and increase the lift-drift ratio of the wing surface.

A further object of the invention is in providing an improved pilot vane which will cooperate with the aerofoil wings to locate the center of lift in the center of the wing area.

A still further object of the invention is to provide an airplane with an improved pilot vane which is disposed in a manner with respect to the wings of the plane so as to provide means for changing the effective lift of the wings at a particular speed without changing the angle of incidence.

Still another object of the invention is in providing an airplane with a cooperable forwardly extending pilot vane which will provide for the center of lift of the plane remaining more localized in fore and aft positions when the angle of incidence of the wings is changed within practicable limits.

Other and further objects will appear in the specification and be specifically pointed out in the appended claims, reference being had to the accompanying drawing, exemplifying the invention, and in which:

Figure 1 is a fragmentary plan view of a portion of an airplane showing this improved pilot vane as forming a part thereof.

Figure 2 is a transverse section taken approximately on the line II—II of Fig. 1.

Referring by numerals to the accompanying drawing 1 designates the fuselage of the airplane and extending therefrom on each side is an aerofoil wing 2, each wing comprising an upper disposed wing camber 3 and a lower disposed wing cord 4 which are spaced from one another by the front and rear spars 5 and 6 respectively. Disposed forwardly of the front spar 5 is the leading edge 7 of the wing nose 8 of each wing.

Mounted in each wing 2 are a series of spaced longitudinally disposed ribs 9 each having an extension 10 extending through and forwardly of the nose 8, the forward end of each extension providing a bearing for the support of respective longitudinal and horizontal disposed alining shafts 11 and 12 which are located on each side of the fuselage 1.

Each shaft 11 is located adjacent each wing end and whereas each shaft 12 is located on each side of the fuselage and rigidly fixed to each shaft 11 is an arcuate pilot vane section 13 and depended from each shaft 11 is a pair of levers 14 each having a connecting rod 15 secured thereto which extends to a respective operating lever 16, said operating levers being secured to an operating shaft 17. Rigidly fixed to each shaft 12 is an arcuate pilot vane section 18 and depended from each shaft 17 is a pair of operating levers which are similar to the operating levers 14 of the pilot vane section 13 and connected to each of the depending levers of the shaft 12 is a connecting rod 19 each of which are connected at their opposite ends to a respective operating lever 20 which are secured to the operating shaft 21.

In the operation of an airplane having this improved pilot vane as a part thereof which comprises the pilot vane sections 13 and 18, as the airplane is moved forward by thrust of the propellers 22, the vanes upon being held in alinement in the position shown in Fig. 2 will cause the upward deflection of air strata into which the nose 8 of the aerofoil wings enters and follows, the layer of air designated by the arrow A will be deflected upwardly between the alining pilot vane sections and the nose 8 of the wings and consequently the air pressure on the leading edge 7 of the nose 8 will be eliminated. In addition the concave surfaces 23 of each pilot vane section will cause an upward deflecting of an air layer as designated by the arrow B above the pilot vane and the nose 8 of the wings and the two layers of air as designated by the arrows A and B will provide a stronger suction lifting effort of all top areas of the wing rearwardly with the greatest relative

increase of lifting effort being more noticeable as the rear edge of the wings is approached, due to the two air layers A and B being cambered above the longitudinal center of the wings as indicated by the arrow C. This cambering of a greater depth of air strata above the longitudinal center of the wings will cause a greater partial vacuum to be maintained next above the wing surface thereby providing a greater lifting effort to the wing.

As the negative pressure is located at the pilot vane sections 13 and 18 which is a distance forward of the wings 2 it follows that the center of the net lift of the wings will be rearward from its present critical position as is experienced in the use of the present airplane wing.

In the present type of airplane and in the operation thereof the leading edge 7 of the nose 8 in flight engages and deflects a strata of air upwardly which results in a downward pressure component on the nose of the wing forward of its maximum cross section as indicated by arrow D and this upwardly deflected air cambering over rearwardly portions of wing produces its maximum suction effort forward of arrow E which arrow indicates the approximate position of resultant net upward lift. Obviously the lift due to upwardly deflected air currents is greater than the net lift and as the downward component at arrow D is located relatively close to arrow E, it is readily seen that with variations of speed and angle of incidence of the plane, the position of net lift does change its position critically and to an appreciable extent. When the aerofoil wing as shown is provided with a pilot vane to assume the duty of causing the upwardly deflected air currents at a position forward of main wing structure as indicated by arrow F, it follows that the resultant net lift would be located rearwardly and the distance of the negative force located at F forwardly of maximum section of the wing is to the distance of the center of lift located at arrow C, rearwardly of maximum section approximately as the present distance of center of negative force located at arrow D forward of center of maximum section, is to present center of lift located at arrow E rearwardly of maximum section of wing. The distance from arrow F to arrow C is greater than the distance of arrow D to arrow E thus it follows that the position of the net lift of arrow C would always be more stably located under various flying conditions than would the net lift as heretofore positioned at arrow E of the aerofoil wing without a pilot vane.

The use of the pilot vane sections 13 and 18 disposed in the manner as shown, forwardly of the nose 8 of the wings 2, will permit a redistribution of the dead loads such as the necessary landing gear and power plant

weights of the airplane due to the localizing of the net lifting force to the position as shown by arrow C. This positioning of the center of lift at a position between the spars 5 and 6 of each wing 2 will provide for mounting the motors 25 between the wing spars from which position pusher screws 22 can be actuated. As shown, it is desirable to place the axis 24 of each motor about which the propellers revolve a distance above each rear wing spar 6, as in flight each propeller partially evacuates the space immediately preceding it, and will cause an additional suction component which assists the cambering air strata in sustaining the airplane wing.

With this improved pilot vane disposed forwardly of the wings, the effective lift of the wings at a particular speed depends upon the magnitude of the upwardly deflected air strata which is principally caused by the pilot vanes and therefore it follows that the lateral balance during straight flight of the airplane or the necessary banking of the plane at turns can be controlled by the simultaneous changing of the negative angle of incidence of the end pilot vane sections 13 in opposite directions to one another. Assuming the longitudinal balance requiring a normal negative setting of the end pilot vane sections 13 and center pilot vane sections 18 to approximately five degrees, and should it be desired to elevate the right hand wing, the shaft 17 which is cooperable with the right hand pilot vane 13 is operated to a position wherein the right hand vane 13 will be moved approximately two degrees more negative or to a position of approximately seven degrees negative, and simultaneous therewith the left hand pilot vane 13 is moved by its operating shaft 17 to a position of approximately 2 degrees less negative incidence or to a position of only three degrees negative angle. With the respective pilot vane sections 13 set to these positions, it follows that the right wing enters the stronger upward deflected air strata which thus elevates the left wing due to the respective increase and decrease of sustaining ability of respective wings. Longitudinal balance does not change with the momentary changes of setting of the end pilot vane sections 13 as their average angle of incidence remains the same as the center pilot vane sections 18.

What I claim is:—

1. In an airplane the combination of an aerofoil wing and a pilot vane having a convexed under surface and a concaved upper surface located forwardly of said wing above the wing chord thereof, said pilot vane adapted to cause deflected air strata to cooperate with the upper contour of said wing.
2. In an airplane the combination of an aerofoil wing and a pilot vane disposed forwardly thereof, said pilot vane having a convexed lower surface and a concaved upper

surface and being divided into sections and adapted to cause deflected air strata to cooperate with said wing, the end sections of said pilot vane being separately operable from the other sections.

5. In an airplane the combination of an aerofoil wing and a pivoted pilot vane having a convexed lower surface and a concaved upper surface disposed forwardly thereof, said pilot vane being divided into sections and adapted to cause deflected air strata to simultaneously cooperate with the top and bottom surfaces of said wing.

10. 4. In an airplane, a pilot vane having a convexed lower surface and a concaved upper surface disposed forwardly of the aerofoil wing and on a plane above the wing chord thereof adapted to load the airplane structure with an air-load during flight.

15. 5. In an airplane, a pilot vane having a convexed lower surface and a concaved upper surface disposed forwardly of the aerofoil wing and on a plane above the wing chord thereof adapted to load the airplane structure with an adjustable air-load at a point forward of the wing during flight for trimming the longitudinal stability of the airplane.
